CASEMENT LATCHING DEVICE

William H. Creber, Los Angeles, Calif.

Application June 1, 1935, Serial No. 24,534

7 Claims. (Cl. 16—144)

This invention relates to an adjustable latch for hinged members, herein designed for use in connection with a casement, but adaptable to general use.

5 The principal object of the invention is to provide a simple, inexpensive and positive latch for adjustably latching a casement at its hinge from moving relative to its jam or frame.

Another object of the invention is to obtain 10 adjustable latching of a casement by means of a bolt slidable in one direction to open the latch and slidable in the other direction to close the latch, but not requiring turning of the bolt to either latch the casement or unlatch it.

15 Another object of the invention is to provide a casement latch adapted to coact with the casement hinge; which will normally rest in a position positively latching the casement from moving; which will grip both wings of the casement 20 hinge in effecting the latching function, and which will release the wings of the hinge to move freely relatively by movement of the latch member in one direction and again latch the hinge wings from relative movement by movement of 25 the latch member in the opposite direction.

Another object is to provide a casement latch adjustable in a considerable plurality of positively held positions, and one that is void of springs, snaps, lock screws or any of the numerous 30 forms of latching instrumentalities employed in window latches.

Still another object is to provide a casement latch for installation on the inside and particularly in close proximity to the rabbet between 35 the sash and frame, in which location it is most inaccessible from the outside and therefore unusually effective to prevent further opening of the casement from a partially open ventilating position.

40 And still another object of the invention is to provide an adjustable casement latching device which lends itself to the obtaining of both adjustment and latching functions by means of a single slidable latch member adapted to be moved in a plane parallel to the axis of the hinge to obtain the advantage of gravity for holding the latch member in its latching functioning position.

Other objects and advantages will appear in the attached specification and claims.

50 Fig. 1 is an elevational view of one form of the present invention showing the combined slide bolt and latch secured to a sash slightly ajar relative to the jam.

Fig. 2 is another elevational view showing a 55 modified form of the present invention also secured to a sash slightly ajar relative to the jam.

Fig. 3 is a plan view looking downward on the axis line of the casement hinge and showing the form of the present invention illustrated by Fig. 1.

60 Referring to the drawing and for the present

to Figures 1 and 3, 10 designates a casement adapted for swinging motion relative to a jam or frame indicated at 11. Supporting the casement 10 for horizontal swinging motion from the frame 11 is a hinge 12 having two wings or leaves 13 and 14, the leaf 13 being secured to the casement 10 and the leaf 14 being secured to the frame or jam 11. This hinge is of the conventional form and is jointed at its leaf axis by the usual pin 15. It will be obvious that this hinge offers two 10 exposed bar edges 16 and 17 comprising the top or bottom edges of the two leaves 13 and 14 disposed between the axis of the hinge and the outer portions which engage the sash and frame, respectively. Since these exposed and coincident 15 bar portions 16 and 17 extend radially from the hinge axis, and swinging toward and from each other, upon closing and opening the casement 10, the two upper or lower edges 16 and 17 therefore would accommodate a toothed, recessed or 20 notched radius disk or mushroom shaped portion of the latch member 18 when raised and lowered into engagement with the upper or lower coincident edges 16 and 17 of the hinge leaves 13 and 14, whereby the hinge is latched and the casement 25 latched accordingly. Hence the present invention is found to include a bolt or slide bar part 19 slidably mounted preferably by a guide plate or base member 20 provided with guides 21^a and 21^b receiving the slide bar part 19 and which is 30 secured to the casement (sash) 10 and which slide bar part 19 is preferably formed to include an integral and outwardly off-set portion 18 provided with irregularly spaced notches 21 for engagement with the edges 16 and 17 of the hinge 35 wings 13 and 14.

It will be seen that if the invention is installed vertically, above the hinge, the slidable bolt 19 and flanged disk 18 will constitute a gravity inclined member which will maintain in any selected position the casement 10 from moving 40 relative to the jam or frame.

To change the position of the casement, it will be obvious that this simple latch only requires that the bolt 19 be raised, the casement moved to 45 the desired position, and the bolt 19 again moved into engagement with the hinge leaves 13 and 14.

Referring now to Fig. 2, a modified form of making the slidable bolt and latching portion is shown. The numeral 22 indicating this main 50 part of the invention consisting of a ribbon of metal is bent to suffice the requirements of both the slide bolt 19 and the notched portion 18. All other parts being the same as illustrated in Fig. 1 are indicated by the same numerals. The construction of the modified form of the invention illustrated in Fig. 2 differs from the construction illustrated in Fig. 1, principally, in that a bar stock of substantially one size from end to end is used for the bolt and projecting latching 55 60

- portion 19' and 18', thus integrally forming the movable latch member. The stock being twisted at substantially right angle to the bolt portion 19' and from the angularly projecting juncture 5 point with the bolt portion 19' being twisted spirally to a central point so as to provide the latching portion 18' in which the series of recesses or notches 21 are irregularly spaced for cooperation with the hinge leaves.
- 10 In both forms of the invention, a cylindrical box or hub 23 is formed in the center of the projecting latching portion 18 of the movable latch member to coincide with the axis of the hinge 12 and adapted to fit over the hinge pin 15 and acting 15 as a centering pilot bearing for the vertically movable latch member. Also a grip portion 24 is provided on the bolt 19 to facilitate its manipulation.

While I have illustrated preferred forms of the 20 present invention, it will be understood that various changes may be made and other forms employed without departing from the spirit of the invention as set forth in the appended claims.

Thus it will be seen that I have provided a 25 singular adjustable and positive latching device which is simple, inexpensive of manufacture, easily installed and novel particularly in its making use of the established hinge found on the casement to complete an adjustable latching apparatus therefor.

I claim:

1. A casement window hinge latch, comprising a base portion having guides for a reciprocal latching member and adapted to be mounted on 35 said window adjacent said hinge, a latching member comprising a bar portion reciprocal in said guides parallel to the hinge axis, and carrying a laterally projecting hinge leaf engaging member, said laterally projecting portion having 40 around its periphery irregularly spaced notches adapted to be brought into engagement with the adjacent edges of the hinge leaves to latch them in any adjusted position of the casement window.

2. A casement window hinge latch, comprising 45 a base portion having guides for a reciprocal latching member and adapted to be mounted on said window adjacent said hinge, and a latching member comprising a bar portion reciprocal in said guides parallel to the hinge axis, and carrying 50 a flanged disk-shaped end portion laterally projecting with respect to said bar portion to span the coaxial edges of the hinge leaves, said flanged disk-shaped portion having around its periphery irregularly spaced notches adapted to 55 be brought into engagement with said coaxial edges of the hinge leaves to latch said hinge leaves in any adjusted position of the casement window.

3. In a casement window and hinge assembly 60 which provides for horizontal swinging movement of said casement window and which embodies a hinge having a vertical pivot axis and at least two leaves one secured to the casement and the other to its frame, the combination of 65 a member forming a base portion and having guides for a reciprocal latching member operative in a vertical plane coincident to the said hinge vertical axis, said base member being mounted on said vertical sash part of said casement, and 70 a slidable latch member reciprocal in said guides for movement parallel to said vertical sash part toward and away from the pivotally-coaxial and adjacent edges of the hinge leaves, said slidable

latch member having its end, being that contiguous to said hinge, notched at irregularly spaced points forming a dentated member adapted to be brought into engagement with the pivotally-coaxial and adjacent edges of both leaves of the 5 hinge to latch them in any adjusted position of the casement window.

4. A casement window hinge latch, comprising a reciprocal latching member comprising a bar portion for reciprocal mounting on one of the hinged elements and carrying an irregularly notched portion adapted to be brought into dentate engagement with the edges of the leaves of the hinge to latch them in any adjusted position of the casement window and carrying a guide 15 portion adapted to engage the pivot pin of the hinge, a pivot pin of said hinge one end of which being formed to project beyond said engagable edges of the leaves of the hinge and adapted to fit within said carried guide portion of said latching member and forming one reciprocal movement guide therefor, and a base portion adapted to be mounted on said one of the hinged elements and having guides for said bar portion of said latching member and forming another reciprocal 25 movement guide therefor.

5. A casement window hinge latch, comprising, in combination, a bearing member for the reciprocal movement mounting of a slidable hinge latch member and adapted to be mounted on one of the hinged elements, a slidable latch member reciprocal in said bearing member parallel to the hinge axis, said latch member carrying an irregularly notched portion adapted to be brought into engagement with the adjacent edges of the 35 hinge leaves to latch them in any adjusted position of the casement window, and said latch member also carrying a guide member adapted for reciprocal bearing movement over the adjacent end of the hinge pivot pin.

6. In a casement window hinge latching device 40 means for latching the leaves of said hinge in any adjusted position of said casement window including, a slidable latch member comprising a bar-shaped member forming a bolt adapted to be 45 mounted on one of the hinged elements for reciprocal movement parallel to the hinge axis and a laterally projecting member carried by said bolt and having around its periphery irregularly spaced notches adapted to be brought into engagement with the adjacent edges of the hinge leaves and a guide member carried by said bolt and adapted to operate as a bearing to reciprocally engage the pivot pin of the hinge.

7. A casement window hinge latch, comprising 50 a slidable latch member adapted to be slidably mounted on one of the hinged elements, means for slidably mounting said latch member on said one of said hinged elements reciprocal parallel to the hinge axis, said slidable latch 60 member carrying a laterally projecting hinge leaf engaging member, said laterally projecting portion having a turned rim with irregularly spaced notches formed in said turned rim adapted to be brought into engagement with the adjacent edges 65 of the hinge leaves to latch them in any adjusted position of the casement window, and a hub formed in said laterally projecting portion and adapted to fit over the pivot pin of the hinge, said hub acting as a supplementary mounting 70 means for said latch member to slide parallel to the hinge axis.

WILLIAM H. CREBER.
